UNITED STATES PATENT OFFICE

WILLIAM P. MCHUGH, OF ST. LOUIS, MISSOURI

MINIATURE THEATER

Application filed April 8, 1929. Serial No. 353,431.

My invention relates to improvements in miniature theaters, and has for its primary object a device which can be used both as a loud speaker for radios or phonographs so that, when it is in use, it will represent a miniature stage.

A further object is to construct a device which can be installed in phonographs or loud speakers, which will have all the appearance of a stage and in which one or more curtains, similar to those employed in theaters, are automatically operated thereby carrying out a full stage effect.

A still further object is to construct a device which will represent a stage in miniature and which is provided with a curtain to roll up the same as a drop curtain on a large stage, and with curtains which will move aside representing the draw curtain of a stage and which is provided to the rear of these curtains with a translucent screen on which scenery may be painted or which can be used with a television device on which pictures can be thrown and appear to the audience.

A still further object is to construct a miniature theater, which is provided with doors which, upon being opened, will automatically operate one or a series of curtains and at the same time illuminate predetermined portions of the device.

In the drawings: Fig. 1 is a perspective view of one form of my device showing the same when the doors are opened and the curtain raised;

Fig. 2 is a vertical longitudinal section of the same taken on the line 2-2 of Fig. 3 showing the manner in which the various curtains are operated;

Fig. 3 is a vertical cross section taken on the line 3-3 of Fig. 2; and

Fig. 4 is an enlarged fragmental section showing the manner of operating the draw curtain.

In the construction of my device I employ a casing 5 which may be of any desired shape. This casing is provided with a proscenium arch 6, adjacent which are projecting representations of boxes 7. 8 represents an orchestra pit in which I may, if de-

sired, place figures representing musicians of various musical instruments. These, however, are not shown since they form no particular part of my invention. To the rear of the proscenium arch 6 and within the casing or housing 5 is placed a roller 9 to which a drop curtain 10 is attached.

The roller 9 is carried in bearings 11 and has secured thereto a gear 12. The gear 12 meshes with a gear 13 mounted on a shaft 14, which is carried in a suitable bearing and which shaft is provided with a drum 15 around which a cable 16 is secured. This cable may be either a cord or it may be formed of wire. To one end of the cable 16 is secured a weight 17, the purpose of which will be explained in detail later. The cable 16 passes around a sheave wheel 18, thence through an opening 19 formed approximately in the center of the front of the orchestra pit, and the opposite end of the cable 16 is attached, at the point indicated by the numeral 20, to the closure or door 21 of the casing 5. The closure or door 22 of this casing, as well as the door 21, is preferably covered with a fabric 23 on which are painted representations of boxes 24 so that when the doors are opened a full illusion of a theater will be obtained.

Carried by the top 25 of the casing 5 is a slotted bracket 26 through which a pin 27 extends. The top 25 also carries brackets 28 and 29 to which tracks 30 and 31 are pivotally secured. The ends of these tracks are slotted as indicated by the numeral 32 into which the pin 27 extends.

The pin 27 projects forwardly through the slot 33 formed in the bracket 26 and is designed to be contacted with by a bracket 34 carried by the lower end of the drop curtain 10. The drop curtain is also provided at its lower end with a stiffening member 35, which may be either of wood or metal so as to hold the curtain 10 straight.

The track 31 is provided with an extension 36 which projects beyond the bracket 29 and which is designed to be contacted with by the end of a screw 37. Carried by the tracks 30 and 31 are rollers 38 to which brackets 39 are secured. These brackets in

turn are secured to the upper end of draw curtains 40. It will be noted from Fig. 2 that the normal position of the tracks 30 and 31 is such that they incline downwardly toward the center so that the rollers 38 will have a tendency to roll down and keep these draw curtain in closed position. The outer ends of the draw curtains 40 are permanently secured to the tracks by means of brackets 41 so that the entire curtain will not slide or draw toward the center of the stage.

To the rear of the draw curtains 40 is mounted a translucent screen 42. This screen may have designs of any desired type painted thereon or it may be left blank so that when a television device, such as is illustrated at 43, is employed the resulting figures therefrom will appear on the screen. 20 44 represents an amplifier which is mounted to the rear of the translucent screen 42 and from which the sound emanates.

In the orchestra pit are placed lights 45, which may be illuminated upon the opening 25 of the door and to the rear of the translucent screen 42 I may place lights 46, which may also be illuminated so that in the event of scenery being painted on the translucent screen, it will become visible.

30 The operation of my device is as follows: Assuming the doors to be closed, the first step will be to open the doors 21 and 22. As the door 21 is opened, it will exert a pull on the cable 16 unwinding a portion 35 thereof from the drum 15 and raising the weight 17 simultaneously with the raising of the drop curtain 10. As the drop curtain 10 approaches its uppermost limit of raising, the bracket 34 will contact with the 40 pin 27 elevating the inner ends of the tracks 30 and 31 so that instead of sloping downward toward the center, they will slope downward toward the ends. This permits the rollers 38 to roll toward the brackets 45 28 and 29 moving the draw curtains side- 50 wise and disclosing the translucent screen thus giving the impression of the stage curtains being operated, then the amplifier can be brought into action, completing the illusion, which will be still more forcibly impressed on the audience or listeners if the device has a television accessory. If the television device or accessory, however, is not used, the lamps 46 are illuminated thus 55 giving the full effect of a theater.

In the event it is not desired to use the draw curtains 40, the screw 37 can be turned down so as to depress the end 36 of the track 31. This will simultaneously raise the 60 track 30 and hold the draw curtains in opened position at all times. Therefore, with my device I may use either the drop curtain only or use both curtains, depending entirely, of course, on what effect I desire to carry out.

Upon closing of the doors, and especially the door 21, the weight 17 will descend causing the drop curtain 10 to unroll and descend, and if this drop curtain has operated the draw curtains 40, these curtains will close automatically as soon as the pin 27 reaches its lowest position in the slot 33 of the bracket 26.

I do not desire to limit myself to the peculiar shape of casing disclosed because, as 75 aforementioned, this casing may be made of various shapes; it may be built in a radio or phonograph cabinet, or may be so constructed as to be set in cabinets which have already been constructed. I may also, if desired, 80 eliminate the lighting features of my device without departing from the spirit of my invention.

Having fully described my invention, what I claim is:—

1. A miniature theater comprising a casing having an opening therein, a closure for said opening, a roller mounted in said casing to the rear of said opening, a drop curtain having a weighted lower edge carried by said roller, means for winding said curtain on said roller as said closure is opened, means for unwinding said curtain as said closure is closed, a draw curtain located in said casing to the rear of said drop curtain, and means carried by the lower edge of said drop curtain for automatically opening and closing said draw curtain by gravity as the drop curtain is raised and lowered.

2. A miniature theater comprising a casing having an opening therein, a closure for said opening, a roller mounted in said casing to the rear of said opening, a drop curtain having a weighted lower edge carried by said roller, means for winding said curtain on said roller as said closure is opened, means for unwinding said curtain as said closure is closed, a draw curtain located in said casing to the rear of said drop curtain, gravity means for automatically opening and closing said draw curtain as the drop curtain is raised and lowered, means carried by the lower edge of said drop curtain for operating said gravity means, and separate means for retaining said draw curtain in opened position.

3. A miniature theater comprising a casing having an opening therein, a closure for said opening, a roller mounted in said casing to the rear of said opening, a drop curtain having a rigid lower edge carried by said roller, means for winding said curtain on said roller as said closure is opened, means for unwinding said curtain as said closure is closed, a draw curtain located in said casing to the rear of said drop curtain, means carried by the lower edge of said drop curtain for causing the automatic opening and closing of said draw curtain by gravity as the drop curtain is raised and lowered, a translucent screen lo-

cated to the rear of said curtain, and means for illuminating said screen.

4. A miniature theater comprising a casing having an opening therein, a closure for said opening, a roller mounted in said casing, a roller curtain extending across said opening and carried by said roller, means for winding said curtain on said roller as said closure is opened and for unwinding the same as said closure is closed, a draw curtain across said opening, and movable supporting means for said draw curtain and actuated by said first-mentioned curtain to cause gravity-controlled opening and closing movement of the latter as said first-mentioned curtain is raised and lowered.

In testimony whereof I have affixed my signature.

WILLIAM P. McHUGH.
